DESIGN FOR A DEHYDRATOR FOR FRUITS, VEGETABLES, OR THE LIKE

Frank L. Monroe, White Plains, N. Y.

Application July 2, 1943, Serial No. 110,586

Term of patent 7 years

(Cl. D49—1)

To all whom it may concern:

Be it known that I, Frank L. Monroe, a citizen of the United States, residing in White Plains, county of Westchester, State of New York, have invented a new, original, and ornamental Design for a Dehydrator for Fruits, Vegetables, or the like, of which the following is a specification, reference being had to the accompanying drawing, forming part thereof.

Fig. 1 is a perspective view of a dehydrator for fruits, vegetables, or the like embodying my new design;

Fig. 2 is an end elevational view thereof, on a slightly reduced scale.

I claim:

The ornamental design for a dehydrator for fruits, vegetables, or the like, as shown.

FRANK L. MONROE.
